UNITED STATES PATENT OFFICE.

WILFRED LEWIS, OF HAVERFORD, PENNSYLVANIA, ASSIGNOR TO THE TABOR MANUFACTURING COMPANY, OF PHILADELPHIA, PENNSYLVANIA, A CORPORATION OF PENNSYLVANIA.

MOLDING MACHINE.

Application filed January 16, 1922. Serial No. 529,447.

To all whom it may concern:

Be it known that I, WILFRED LEWIS, a citizen of the United States of America, and resident of Haverford, in the county 5 of Montgomery, in the State of Pennsylvania, have invented certain new and useful Improvements in Molding Machines, of which the following is a true and exact description, reference being had to the accompanying drawings, which form a part 10 thereof.

My invention relates to jar molding machines adapted to pack sand on a pattern in a flask by jarring and then roll over the 15 mold and draw the pattern and, more particularly, my invention relates to the type of machines of this class known as combination trunnion machines, as distinguished from jar combination machines in which the 20 roll over plate is pivoted to the lifting and roll over mechanism at the side of the jarring machine element of the apparatus.

Hitherto, roll over trunnion machines have, so far as I am aware, been constructed 25 with roll over trunnions permanently attached to the roll over plate, with the effect of concentrating a heavy dead load at each end of the plate which is highly undesirable as the first requisites of a good 30 jarring machine are absolute solidity on impact and uniform distribution of the shock. Again, the roll over mechanism must be quick acting, swift and effective and the pattern draw must be well-nigh perfect to 35 properly handle deep patterns with almost parallel sides.

With the above facts in view, it is the object of my invention to provide a combination trunnion machine so constructed that 40 the roll over plate is entirely detached from its trunnions during the jarring of the mold. A further important object of my invention is to so construct the machines that the roll over plate can be adjusted with respect to 45 the axes of the trunnions so as to accommodate flasks of different sizes and so that in rolling over after the jarring of the mold the flask will overbalance the plate, and so that in rolling back after the flask is detached, gravity will assist the back rolling 50 operation. Another improved object of my invention is to control the rolling movement of the roll over plate and flask by power and in such a way that the flask is picked up

squarely before rolling and the pattern plate 55 held firmly in alignment during the drawing of the pattern.

Still another object of my invention is to so connect the trunnion supporting and lifting mechanisms that they will move together 60 in unison.

Another object which I have in view, and which relates particularly to an apparatus in which a shockless jarring machine is used, is to bring the table or head of the 65 jarring machine to the floor level when the roll over plate is at its highest position so that a car can be conveniently used to receive the finished drag mold.

Other objects which I have in view will 70 be best understood as described in connection with the drawings which illustrate an apparatus constructed in accordance with my invention and in which—

Figure 1 is a front elevation of a machine 75 embodying my improvements shown partly in section.

Figure 2 is an end view of the apparatus, certain details being shown in section.

Figure 3 is an end view similar to that 80 shown in Fig. 2 but showing the trunnions in their upper position and the roll over plate and attachments in roll over position.

Figure 4 is a sectional view of the locking mechanism attached to the trunnions and 85 adjustable with respect thereto, the view being taken as on the line 4—4 of Fig. 6.

Figure 5 is a part of the mechanism shown in Fig. 4.

Figure 6 is also the end view of the apparatus shown in Fig. 4, with the locking mechanism shown in cross section on the line 6—6 of Fig. 4.

Figure 7 is a cross sectional view on the line 7—7 of Fig. 4.

Figure 8 is an elevation and modified detail to be explained, and

Figure 9 is a sectional elevation of a detail.

A indicates the jarring machine which 100 may be of any approved kind and construction. A' indicates the plunger or anvil of the jarring machine, the top or table of which is indicated at A². B is the jarring head which rests upon the portion A² of the 105 anvil and supports the table B² on which the roll over plate rests and which is conveniently formed with ribs as indicated at B³.

which can serve as tracks for the truck used to carry away the molds. B⁴ B⁵ indicate sockets for receiving pins attached to the roll over plate for properly centering the 5 plate on the head B², and C is a pin extending down from the jarring head into a guide lug A³ on the cylinder of the jarring machine for holding the jarring head in proper alignment. D indicates bushings 10 pivoted in the sockets B⁴. E is the roll over plate having attached to its lower side the locking bar indicated at E' having, as shown, tapered lugs E² adapted to be engaged by the locking jaws. F, F, indicate 15 pins secured to the roll over plate and adapted to be engaged with the bushings D, as shown in Fig. 1. G, Fig. 1, indicates the flask resting on the roll over plate and provided with trunnions as indicated at G'. H, 20 H, are cylinders secured on opposite sides of the roll over machine and continued, as shown, by sections H' of somewhat smaller diameter in which fit the vertically movable pistons or plungers indicated at H² supporting on their upper ends heads H³ in which are formed bearings H⁴ for the trunnions and above which are secured cap pieces indicated at H⁵. I, I', are adjustable stops secured to the cap pieces H⁵, the function of 25 30 which will be hereafter described. J and J' are the trunnions resting in the bearings H⁴ of the heads H³ and having attached to their outer ends the lever arms indicated at J' by means of which and mechanism to be described, they are oscillated through an 35 arc of 180°. K, K, are arms secured to the trunnions J and extending, as shown, at right angles to the lever arms J'. These arms K are, as shown, provided with adjusting 40 perforations indicated at K', K', etc. L, L, are locking heads supported on the front faces of the arms K and adjustably attached thereto in such a manner that they can be adjusted toward and away from the axes of 45 the trunnions. They are attached to the arms K by clamps indicated at L' and bolts indicated at L², best shown in Fig. 7, and are held in proper adjustment by the locking bolts indicated at M, normally pressed 50 inward by springs M' and withdrawn through handles M². These bolts extend through bearing perforations in the locking heads L, indicated at L³, and the tops of the locking heads are slotted as indicated at L⁴ 55 to give passage to the locking bars E' of the roll over plate. N, N, are pivot pins supported in the head L and supporting the swinging links indicated at N', N', which in turn, through pivot pins N², N² support 60 the rod or bar indicated at N³. O is a head firmly secured to the rod N³ and from which extends the locking jaw indicated at O' and also the downwardly extending arm indicated at O⁷. O² is a sleeve movable on the 65 rod N³ and having a locking jaw indicated

at O³ and the downwardly extending arm indicated at O⁶. O⁵, O⁵, etc. are spring adjusting bolts secured in the sleeves O and O² and by means of which the spring O⁴ can be adjusted. P is a lever pivoted to the arm 70 O⁶ at P' and connected through an arm P² and pivot pin P³ with a link P⁴ pivoted to the arm O⁷ at P⁵. P⁷ is a roller carried on the end of the lever arm P and in position to be engaged by the contact arm Q, see 75 Figs. 1 and 2, as the roll over plate is rolled over by the trunnions.

Secured to the plunger heads H³ and extending downward in the form of cylindrical sleeves enclosing the cylinders H, H', as 80 shown, are frame members indicated at R, to the lower ends of which are connected the beams indicated at R' which connect the two sleeve-like extensions of the frame together and on which are supported the cross 85 beams indicated at R², carrying adjustable contacts indicated at R³ so located that when the frame moves upward these adjustable contacts will come in contact with the shoulders B⁵, B⁵, extending downward from the 90 head of the jarring machine.

H⁶ are ledges on the cylinders H on which the frame R, R', rests in its lower position. h', see Fig. 9, is a stuffing box at the end of cylinder H' and h² is a flange extending 95 outward from the top of plunger H² and to which the casing R is attached by bolts h⁴, as shown. h³ are bolts securing the head H³ to the plunger H².

Secured at the corners of the frame are the 100 pulley wheels S, S, etc. and over these pulley wheels extend cables two of which, anchored at their upper ends, as indicated at S', extend downward, as indicated at S³, under the pulleys S at one end of the framing, thence over the pulleys S at the other end of the framing to an anchorage S⁴, S⁵ indicating a tension adjusting device in these cables.

Two other cables attached to the frame S⁶ 110 on the other side of the machine, extend downward, as shown, at S⁷ under the pulleys S on one side and over the pulleys S on the other side to a point of attachment S⁸, S⁹ indicating a tension adjusting device.

Secured to the ends of the framing by pivot bolts as indicated at T, T, are the cylinders T', T', having ports for the admission of pressure fluid as indicated at T² and T³, T⁵ indicating plunger heads in these cylinders and T⁶ piston or plunger extensions pivotally connected at their tops as indicated at T⁷ to the arms J' of the trunnions J. These oscillating cylinders, and their connections as described, are partially protected by a sleeve-like extension R⁴ of the framing members R, R.

U indicates a tank containing oil and air under pressure, connecting by a conduit U' leading from its bottom, to the cylinders H, 130

U^2 , indicating a controlled valve. From the upper end of this tank extends the conduit U^3 connected with a source of air under pressure and provided with a valve U^4 .

5 Above this valve is the branch U^5 connecting with the port T^3 of the cylinder T' and another branch U^6 provided with a control valve U^7 and connecting with a port T^2 .

While, for the construction indicated, a 10 car such as V' is most conveniently employed for moving the flasks on to and away from the jarring table, other means can, of course, be employed as, for instance, a crane, and in Fig. 8 I have indicated a hook, W , 15 which can be attached to a crane chain through an eye indicated at W' and which will engage the trunnions G' of a mold through its arm W^2 , a counterweight W^3 being employed to balance the weight of the 20 hook.

To describe the operation of the machine, the parts as shown in Figs. 1 and 2 are in the positions they occupy when the roll over plate is resting on the jarring machine and 25 while the jarring operation is performed, the mold having been subjected to the jarring operation, pressure fluid is introduced into the bottom of the cylinders H and the plungers H^2 are moved upward, the plungers 30 moving synchronously, owing to their attachment, together through the frames R , R' , and the framing being maintained in alignment by the squaring cables passing over the pulleys S and connected, as above 35 described. The plungers H^2 in their upward movement carry with them, of course, the trunnions J , J' , with their arms K , K' , and the attached locking heads L , and the locking heads in their upward movement receive in their openings L^4 the locking bars 40 E' of the roll over plate E which comes to the position in the locking head indicated in dotted lines in Fig. 4. Further upward movement of the plungers H^2 lifts the roll over plate from the jarring table and moves it upward.

While the roll over plate is resting on the jarring table and during the first part of the lifting operation, the trunnions and the locking heads attached to the trunnions through the arms K , are held in proper aligned position by the action of the cylinder and plunger T' , T^5 , the valve U^7 in the conduit U^6 being in position to admit air under pressure from the conduit U^3 to the bottom of the cylinder T' and the plunger T^6 pressing the arms J' of the trunnions against the stops indicated at I . After the roll over plate has been lifted from the top 55 of the jarring machine the valve U^7 is turned so as to cut off the air under pressure and connect the conduit U^6 to exhaust and the port T^3 of the cylinder T' being in constant communication through the conduit 60 U^5 , with the source of air under pressure,

this air presses down the plunger which in turn presses down the arm J' of the trunnion to which it is attached, causing the roll over plate to roll over and after the roll over motion has continued through more 70 than 90° , air is again admitted to the bottom of the cylinder T' forcing the plunger upward until the trunnion arm J' is pressed in contact with the squaring stop indicated at I and this contact is maintained during 75 the drawing of the pattern.

After the pattern is drawn the roll over in the opposite direction is accomplished by a similar manipulation of the valve U^7 .

As the roll over plate moves from one 80 drawing position, as shown in Fig. 3, to the position it occupies when deposited upon the jarring machine, the lever P comes in contact with the stop Q and this stop being pivotally attached through the link P^4 to the head O and through the hollow extension O^6 to the head O^2 the effect is to draw the locking jaws O' and O^3 apart to the position shown in Fig. 4 in which position they clear 85 the lugs E^2 and the locking bar E' so that when the roll over plate is deposited on the jarring machine a further downward movement of the plungers N^2 completely detaches and clears the trunnions and locking heads from the roll over plate. The positive and 90 certain action of the unlocking mechanism is insured in my construction by the application of power through the cylinder T' and plunger T^6 to press the trunnion arm J' against the stop I' . It is, of course, obvious 95 that in the roll over motion of the trunnion from the position shown in Figs. 1 and 2 to that shown in Fig. 3, the lever P is rapidly carried out of contact with the stop Q at the beginning of the roll over motion so that the locking jaws will promptly engage and hold the roll over plate through its locking bar E' and this engagement is maintained 100 until in the reverse roll over movement the lever P again contacts with the stop Q .

At the end of the upward movement of the roll over plate the adjustable stops R^3 supported on the cross bars R^2 of the frame portion R' come in contact with the portions B^5 of the shockless jarring machine's head and lift it to a determined level which should be that of the tracks V so that a car V' can readily be run onto the table B^2 to receive or carry away a flask.

I have already described the devices by 120 which the locking heads L are adjusted on the arms K attached to the trunnions J and it will, of course, be understood that this adjustment is highly advantageous for adapting the machine to the use of different flasks in which the center of gravity is at different distances from the surface of the roll over plate. In making the necessary or desirable adjustment of the locking heads it will 125 be obvious that the trunnions should be 130

turned to a position in which the arms K are substantially vertical.

As shown in Fig. 1 and on a larger scale in Fig. 9, a stuffing box indicated at h' is conveniently used at the top of the cylinder H' and to enable this stuffing box to be conveniently got at for adjustment, etc. I have formed the top of the plunger H² with an upwardly extending flange h² to the top of 10 which the head H³ is attached as by bolts h³ and to the under outer side of which I attach the cylindrical member R of the framing as by means of bolts h⁴. This construction, as will be obvious, enables me to readily 15 detach the plunger from the frame member R so that when the plunger is moved upward the stuffing box is conveniently and readily accessible.

Having now described my invention, what 20 I claim as new and desire to secure by Letters Patent, is:

1. In a roll over jar molding machine of the trunnion type comprising a jarring machine, a roll-over plate and means for raising and lowering the roll-over plate situated 25 on opposite sides of the jarring machine, the improvement which consists in the combination therewith of roll-over trunnions secured to the raising and lowering mechanism and 30 locking mechanism for attaching and detaching the roll over plate to and from the trunnions.

2. In a roll over jar molding machine of the trunnion type comprising a jarring machine, a roll-over plate and means for raising and lowering the roll-over plate situated 35 on opposite sides of the jarring machine, the improvement which consists in the combination therewith of roll-over trunnions secured 40 to the raising and lowering mechanism, locking mechanism for attaching and detaching the roll-over plate to and from the trunnions and means for adjusting said locking mechanism to varying distance from 45 the trunnion axis.

3. In a roll over jar molding machine of the trunnion type comprising a jarring machine, a roll-over plate and means for raising and lowering said roll over plate situated 50 on oposite sides of the jarring machine, the combination therewith of trunnions secured to the movable parts of the raising and lowering means, actuating levers secured to said trunnions, lock holding arms also secured to said trunnions, locking means secured to 55 the said arms adapted to engage and disengage the roll over plate, power means secured to the movable parts of the raising mechanism connected to actuate the operating levers of the trunnions and stops for holding the trunnions in fixed positions at the completion of each oscillation.

4. In a roll over jar molding machine of the trunnion type comprising a jarring machine, a roll-over plate and means for rais- 60

ing and lowering said roll over plate, situated on opposite sides of the jarring machine, the combination therewith of trunnions secured to the movable parts of the raising and lowering means, actuating levers secured to said trunnions, lock holding arms also secured to said trunnions, locking means adjustable on the said arms adapted to engage and disengage the roll over plate, power means secured to the movable parts of the raising mechanism connected to actuate the operating levers of the trunnions and stops for holding the trunnions in fixed positions at the completion of each oscillation. 70

5. In a roll over jar molding machine of the trunnion type comprising a jarring machine, a roll over plate and means for raising and lowering said roll over plate situated on oposite sides of the jarring machine, the combination therewith of trunnions secured to the movable parts of the raising and lowering means, actuating levers secured to said trunnions, lock holding arms also secured to said trunnions, locking means secured to the said arms adapted to engage and disengage the roll over plate, pivoted actuating cylinders secured to and moving with the movable parts of the raising mechanism, plungers in said cylinders connected to the actuating levers of the trunnions and stops for holding the trunnions in fixed position at the completion of each oscillation. 80

6. In a roll over jar molding machine of the trunnion type the combination of a jarring machine, a roll over plate cylinder and plungers for raising and lowering the roll over plate situated on opposite sides of the jarring machine, trunnions supported on said plungers, locking means for attaching and detaching the roll over plate to and from the trunnions, a framing connecting the plungers and parallel motion mechanism connected to said framing for maintaining its alignment during its movements with the plungers and insuring the synchronous movement of said plungers. 90

7. In a roll over jar molding machine of the trunnion type the combination of a jarring machine, a roll over plate, cylinder and plungers for raising and lowering the roll over plate situated on opposite sides of the jarring machine, trunnions supported on said plungers, locking means for attaching and detaching the roll over plate to and from the trunnions, a framing connecting the plungers, pulleys secured at the corners of the framing and squaring cables secured to the frame of the machine and running over said pulleys as described to secure the synchronous movement of the plungers. 100

8. In a roll over jar molding machine of the trunnion type the combination of a jarring machine, a roll over plate, cylinder and plungers for raising and lowering the roll 110

- over plate situated on opposite sides of the jarring machine, trunnions supported on said plungers, locking means for attaching and detaching the roll over plate to and from the trunnions, a framing connecting the plungers, means attached to the frame for lifting the head of the jarring machine to a definite height when the plungers are in their upper position.
- 10 9. In a roll over jar molding machine of the trunnion type, comprising a jarring machine, a roll over plate, cylinders and plungers for raising and lowering the roll over plate situated on opposite sides of the jarring machine, trunnions and means for attaching and detaching said trunnions to and from the roll over plate supported on said plungers, the improved constructive details which consist in providing stuffing boxes at the upper end of the cylinders forming the end of the plungers with outwardly extending flanges, and combining therewith a framing connecting the plungers consisting of downwardly extending cylindrical members detachably secured to the outer edges of the flanges and transversely extending beams securing the lower ends of the cylindrical members together.
- 15 10. In a roll over jar molding machine of the trunnion type comprising a jarring machine, a roll over plate and means for raising and lowering the roll over plate situated on opposite sides of the jarring machine, the improvement which consists in the combination therewith of roll over trunnions secured to the raising and lowering mechanism, power mechanism for rotating the trunnions and holding them in fixed terminal position, locking mechanism for attaching the roll over plate to the trunnions comprising springs normally holding the locking jaws in operative position and levers for opening said jaws and lock opening stops secured to the movable members of the means for raising and lowering the roll over plate and adapted to engage and operate said levers when the plate is rolled over after the jarring operation and to release said levers on the succeeding roll over of the plate and before it is lowered to position on the jarring machine.
- 20 25

WILFRED LEWIS.
